United States Patent Office.

FRANK W. MARVIN, OF SACRAMENTO, CALIFORNIA.

Letters Patent No. 79,666, dated July 7, 1868.

IMPROVEMENT IN MARKING-CANS.

The Schedule referred to in these Letters Patent and making part of the same.

TO ALL WHOM IT MAY CONCERN:

Be it known that I, FRANK W. MARVIN, of Sacramento, in the county of Sacramento, and State of California, have invented a new and improved Marking-Can; and I do hereby declare that the following is a full, clear, and exact description thereof, which will enable those skilled in the art to make and use the same, reference being had to the accompanying drawings, forming part of this specification.

This invention relates to a new and useful improvement in the construction of cans or vessels used for containing liquid for marking boxes, bales, packages, and other articles, whereby the same are rendered more convenient, and better adapted to the purpose intended, than those made in the ordinary manner.

And the invention consists in forming a reservoir, in connection with the can, in which the marking-liquid is kept, and in the arrangement of a screw-valve, by which the liquid is discharged into the can, as it is wanted for use, as I will proceed to describe.

Figure 1 represents a vertical section of the can constructed according to my invention, showing the reservoir and the valve, the section being through the line *x x* of fig. 2.

Figure 2 is a cross or horizontal section of fig. 1, through the line *y y*.

Similar letters of reference indicate corresponding parts.

A represents the can proper, with a concave top, B, formed in the usual manner, or similar to those in common use.

C is the reservoir, it being a triangular annular space surrounding the can.

D is the screw-valve, which closes the tube through which the liquid is discharged from the reservoir to the can.

E is the valve-rod, which has a thumb-wheel, F, upon its top end, as seen.

G represents the handle, which is a tube, through which the reservoir is filled.

H represents a cap-screw upon its end, for closing the aperture.

By this arrangement and manner of construction, it will be seen that the can can always be supplied with liquid without trouble or delay, and in quantities suited to the wants of the moment, without leaving a large quantity in the can to evaporate and be lost.

The marking-liquid in the reservoir is always closed from the atmosphere, so that no evaporation can take place; consequently it is always ready for immediate use.

Having thus described my invention, I claim as new, and desire to secure by Letters Patent—

1. In combination with a marking-can, the reservoir C, substantially as and for the purpose set forth.
2. The valve D and tubular handle G, in combination with a marking-can or pot, arranged substantially as and for the purposes described.

FRANK W. MARVIN.
